UNITED STATES PATENT OFFICE.

GOTTHILF ANSGARIUS BETULANDER, OF SÖDERTÖRN'S VILLASTAD, SWEDEN, OSCAR GRAHN, OF LONDON, ENGLAND, AND NILS GUNNAR PALMGREN, OF STOCKHOLM, SWEDEN, ASSIGNORS TO THE RELAY AUTOMATIC TELEPHONE COMPANY, LIMITED, OF LONDON, ENGLAND.

AUTOMATIC TELEPHONE SYSTEM.

1,184,163.

Specification of Letters Patent. Patented May 23, 1916.

Application filed January 18, 1916. Serial No. 72,709.

To all whom it may concern:

Be it known that we, GOTTHILF ANSGARIUS BETULANDER, OSCAR GRAHN, and NILS GUNNAR PALMGREN, subjects of the King of Sweden, residing, respectively, at Villa Castor, Södertörns Villastad, Sweden, Marconi House, Strand, London, England, and 8 Björngårdsgatan, Stockholm, Sweden, have invented new and useful Improvements in 10 Automatic Telephone Systems, of which the following is a specification.

The invention relates to automatic telephone systems of the class in which the numerical selectors are used for establishing 15 but not for maintaining connections, a selector, when once a connection has been completed, disengaging itself from the junction line in question, and putting itself in readiness for another call. In such a system the junctions are divided into groups, 20 each having one or more selectors accessible in common to all lines of the group and on a call one of these selectors is automatically connected to the calling line.

25 The object of the present invention is by reducing the period during which a selector is engaged for any call, to reduce the number of selectors required for a group of junction lines, or to increase the number of junction lines in a group. This is of special importance in systems having impulse transmitters of the ordinary dial type, as in such systems the selector is not operated immediately on its becoming connected to the 30 calling line owing to the fact that the setting of the dial takes some time which is long in comparison with the whole period during which the selector is engaged, since the time occupied by the actual working of 35 the selector does not usually exceed one second. From one or other reason, the time during which a selector is uselessly engaged may, of course, be rather considerable, and therefore it would be necessary to provide 40 every line group with two selectors at least, whereas the provision of only one selector for every group involves considerable advantages.

45 The disadvantage stated above is obviated according to this invention by arranging that a junction shall not be marked as calling until the subscriber operates the dial

whereupon a signal is emitted, which causes the line to be marked. The connecting of the selector to the line is, therefore, deferred to the moment of setting the dial, preferably to the moment when the dial is set free, and consequently, the period for which a selector is engaged is reduced to the least possible.

50 The invention is illustrated by way of example in the accompanying drawing comprising Figures 1 and 2. These figures taken together with Fig. 1 placed above Fig. 2 show a relay system of controlling circuit 65 extension.

The invention is here shown as applied to a system in which the impulse transmitter is controlled electro-magnetically from the exchange, so that the impulses cannot be 70 emitted until a selector has been connected to the junction in question. The invention is, however, not limited to systems of that kind, as it is obvious that it may be used with the same advantage in a system of the 75 usual kind with uncontrolled impulse sending. In the example shown in the drawing all connecting operations are effected exclusively by means of relays in a known manner. The drawing illustrates a connection between a subscriber's station A and a first group-selector S, only such of the relays and circuits as are necessary for explaining the invention being shown.

75 The subscriber's impulse transmitter, which is of the ordinary dial type, is only diagrammatically represented. It comprises a finger disk 1 provided with impulse teeth 2 operating a contact device 3, 4, and with ratchet teeth 5 coöperating with a pawl 90 7 operated by an electro-magnet 6. The pawl 7 coöperates with a lever 8 in such a manner that it is held in its inoperative position after once having disengaged the dial. When the latter reaches its normal position 95 a pin 9 on the disk actuates the lever 8 so that the pawl 7 is returned to engagement with the teeth 5.

The selector S which likewise is of a known type, comprises a series of switching 100 relays 10, a series of auxiliary relays 11, two controlling relays 12, 13 and an impulse relay 14.

When the subscriber removes his receiver

from the hook 16 the receiver 17 and microphone 18 are in the ordinary way branched between the line wires 19 and 20 through a contact 21 closed in the normal position of the dial. A circuit *a* is thereby closed extending from battery through a line relay 23, and line branches 19 and 20. Relay 23, upon energizing, operates a junction finder common to a group of subscribers' lines, to test the junctions 24, 25, and to energize those relays 30 and 31 which correspond to an idle junction. The junction finder arrangement is not shown here as being of no importance for the present invention, but is fully described in the co-pending application, Serial No. 832,471, and in British Patent No. 9840 of 1914.

Relays 30 and 31 complete a circuit *b* extending from earth through a resistance 32, one winding of an impulse relay 33, both line branches and the other winding of relay 33 to battery. Relay 33 therefore operates and cuts into circuit *c* a slow-acting relay 35 which closes over part of a third wire 38 extending along the talking connection, a circuit *d* locking relays 30 and 31. The completion of this circuit energizes a cut-off relay 36 which cuts out line relay 23. The operating circuits of relays 30 and 31 are thus opened but said relays nevertheless remain energized over circuit *d*. Relay 35 upon operating, also closes a circuit *e* over third wire 38 to a call relay 41 assigned to the junction 24, 25. Relay 41 operates and prepares the circuit of a selector connecting relay 43 pertaining to the same junction. The selector, however, according to the invention cannot be connected to the line until the subscriber has set his dial. When the subscriber releases the dial, after having set it to the desired figure, a marking relay 44 pertaining to the same junction is operated in the manner described below, and causes the selector to be connected by means of relay 43 to the line branch 24 over which the selector is then operated.

The selector, which is common to a plurality of junctions, can be connected by means of relays 43 to any of these junctions, relays 44 controlling the circuits of relays 43 in such a manner that only one calling junction can be connected to the selector at any one time as will now be described. Relays 41, 43, 44 for only two junctions are represented.

The connection of the subscribers' line to the junction 24, 25 has been completed within a very short period of time and before the subscriber has operated the dial. When the subscriber thereupon turns the dial, the receiver and the microphone are cut off at contact 21, and magnet 6 is cut in between the line branches through contact 45 and impulse contact 3, 4. During

the setting of the dial, however, magnet 6 is short-circuited through a contact 46, which at the same time keeps the line circuit closed. At the end of the movement of the dial contact spring 3 rests on the top of a tooth 2, contact 3, 4 being thus open, and the point of pawl 7 lies between two teeth 5. At the moment when the subscriber releases the dial contact 46 is opened, whereby the line circuit is interrupted. The dial is, however, immediately turned back half a tooth through the action of a spring and is stopped in the corresponding position by pawl 7. In this position contact 3, 4 is again closed. The line circuit is therefore again closed this time, however, through magnet 6. The latter however does not operate immediately as the line current is weakened by resistance 32. The brief interruption of the line current has, however, caused relay 33 to release its armature for a moment, whereby two circuits *f* *g* are established, *f* through a slow acting relay 49 and *g* through relay 44. Relay 49 cuts itself into a locking circuit *h* and prepares the circuit of a slow acting relay 52. Relay 44 locks itself over circuit *i*. After relay 33 has again attracted its armature, and if the selector is engaged, nothing will occur until the selector is disengaged, as the dial remains in its wound-up position.

When the selector is set free, which is indicated by connecting relay 43 in question releasing its armature, a circuit *k* is closed. Relay 43 operates, cuts itself into a locking circuit *l* and connects line branch 24 to impulse relay 14 of the selector. At the same time a circuit *m* is closed through the back contacts of the other relays 43 and through all switching relays 10 whereby the latter are energized.

As the selector is now connected to the line branch 24 a circuit *n* is established through relay 52 and impulse relay 14. The relay last mentioned operates and cuts slow-acting relay 12 into circuit *o*. Relay 52 attracts its armature thereby short circuiting resistance 32 over third wire 38. The line current is thereby strengthened, so that magnet 6 attracts pawl 7, and releases the dial. Pawl 7 is then retained in its disengaged position by lever 8. During the return movement of the dial, the line circuit is broken a certain number of times at contact 3, 4. For every interruption of the current impulse relay 33 releases its armature, thereby sending an impulse each time over circuit *f* through slow-acting relay 49 to retain its armature in its attracted position. Relay 33, each time it deenergizes, breaks circuit *n* of impulse relay 14 and slow-acting relay 52. The relay last mentioned keeps its armature attracted, while relay 14 releases its armature each time thereby sending an impulse through slow-acting relay 12 over circuit *o*

o' to keep its armature attracted during the sending of the impulses. When impulse relay 14 releases its armature for the first time, an impulse is sent by circuit p through relay 13 and by circuit q q' q through first auxiliary relay 11. Relay 13 operates and locks itself over part of circuit p and relay 11 likewise operates and locks itself over part of circuit q. The first switching relay 10 is, thereafter, maintained energized, as long as the impulse lasts, over circuit r. When the impulse ceases first switching relay 10 releases its armature. The next impulse therefore passes along circuit q q' q energizing the second auxiliary relay 11 and the second pair of relays 10, 11 act under the second impulse in the same manner as described in respect of the first pair of relays. Thus, for every new impulse corresponding to an interruption of the line current a corresponding pair of relays 10 and 11 is operated until the dial reaches its normal position. The line circuit then remains closed through the receiver and microphone. Consequently impulse relay 14 also remains energized and owing to the interruption of circuit o o' slow-acting relay 12 releases, whereby a circuit s is closed from earth through contacts 85 of the deenergized relays 10 and contacts 86 of the first energized relay 10 and further to a switching device (not shown) which is adapted to effect in a known manner the testing of the junction lines belonging to the group selected, and then to send a current 35 through a connecting relay 40 by means of which junction 24, 25 may be connected to an idle junction 87, 88 of the group selected. This operation, which has no bearing on the present invention, is fully described in the co-pending application No. 27,685 and in British Patent No. 6210 of 1914, and need not therefore be further described in this connection. When impulse relay 33 was finally energized after the last impulse, it 45 broke circuit f and therefore after an interval and subsequently to the deenergization of relay 12 slow-acting relay 49 releases its armature breaking circuit n whereby relay 52 is deprived of current. The transfer relays 33, 35, 49 and 52 belonging to the junction 50 24, 25 are therefore in the same condition as before the connecting of the selector. Connecting relay 40 upon energizing, cuts itself in a known manner into a locking circuit over third wire 38. At the same time circuit e of relay 41 is opened, said relay in its turn opening circuits g i h l of relays 43 and 44. When relay 43 releases its armature, the selector is restored to its normal 55 condition. If at this moment there is a call on one or more other junctions of the same group, a circuit t is established through back contacts of relays 44 belonging to non-calling junctions, front contact of the relay 44 belonging to the first of the calling junc- 60 65

tions and relay 43 of the same junction. The junction in question is thereby connected to the selector as before described. Thus, by making the marking relays 44 control the circuits of the selector connecting relays 43 in the manner described, the object is attained that only one calling junction is connected to the selector at any time. 70

By the next operation of the dial a selector of the next selecting stage is operated 75 in a similar manner. Upon putting back the receiver after the termination of the conversation the line circuit is opened, the talking connection being then disconnected by relay 35 releasing its armature and opening 80 the locking circuits of the connecting relays 30, 31 and 40.

In case for instance two selectors are allotted to every group of junctions, each junction may be provided with two selector connecting relays 43, viz., one for each selector, 85 the circuits of which are in a similar manner controlled by corresponding marking relays 44 so as to prevent more than one junction being simultaneously connected to the selector, as will be readily understood. 90

What we claim is:—

1. In an automatic telephone system, the combination of subscribers' lines, impulse transmitters at the subscribers' stations, 95 junction lines at the exchange, a numerical selector accessible in common to a plurality of junction lines, means for connecting the selector to a calling junction line, and means actuated by the operation of the subscriber's impulse transmitter for marking the junction line as calling. 100

2. In an automatic telephone system, the combination of subscribers' lines, impulse transmitters at the subscribers' stations, 105 junction lines at the exchange, a numerical selector accessible in common to a plurality of junction lines, a relay adapted to connect the selector to a calling junction line, a marking relay adapted to control the relay first mentioned, and means actuated by the subscriber's transmitter for energizing the marking relay. 110

3. In an automatic telephone system, the combination of subscribers' lines, impulse transmitters at the subscribers' stations, junction lines at the exchange, a numerical selector accessible in common to a plurality of junction lines, a relay assigned to each junction line and adapted to connect the selector to a calling junction line, a marking relay assigned to each junction line and adapted to control the relay first mentioned, and means actuated by the subscriber's transmitter for energizing the marking relay. 115 120

4. In an automatic telephone system, the combination of subscribers' lines, impulse transmitters at the subscribers' stations, junction lines at the exchange, a numerical selector accessible in common to a plurality 130

of junction lines, means for connecting the selector to a calling junction line, means actuated by the operation of the subscriber's impulse transmitter for marking the junction line as calling, and means for preventing more than one junction line being connected to the selector at any one time.

5. In an automatic telephone system, the combination of subscribers' lines, impulse 10 transmitters at the subscribers' stations, junction lines at the exchange, a numerical selector accessible in common to a plurality of junction lines, a relay adapted to connect the selector to a calling junction line, a 15 marking relay adapted to control the relay first mentioned, means actuated by the subscriber's transmitter for energizing the marking relay, and means for preventing more

than one junction line being connected to the selector at any one time.

6. In an automatic telephone system, the combination of subscribers' lines, impulse transmitters at the subscribers' stations, junction lines at the exchange, a plurality of numerical selectors, each accessible in common to 25 a plurality of junction lines, a relay for each selector assigned to each junction line and adapted to connect its selector to a calling junction line, a marking relay for each of the first mentioned relays and adapted to 30 control such relay, and means actuated by the subscriber's transmitter for energizing one or other of the marking relays.

GOTTHILF ANSGARIUS BETULANDER.
